United States Patent Office.

WILLIAM S. RYERSON, OF NEW YORK, N. Y., ASSIGNOR TO HIMSELF, AMOS L. TRIPP,
AND CHARLES CHAMBERS, OF SAME PLACE.

Letters Patent No. 91,488, dated June 15, 1869.

IMPROVEMENT IN BOAT-DETACHING APPARATUS.

The Schedule referred to in these Letters Patent and making part of the same.

To all whom it may concern:

Be it known that I, WILLIAM S. RYERSON, of the city and State of New York, have invented and made a new and useful Improvement in Detaching Boats; and I do hereby declare the following to be a full, clear, and exact description of the said invention, reference being had to the annexed drawing, making part of this specification, wherein—

Figure 1 is an elevation of the said means for detaching boats;

Figure 2 is an elevation of the same at one end, with the parts partially moved for detaching the boat; and

Figure 3 is a section at the line *x x*.

Similar marks of reference denote the same parts.

This invention is designed for detaching boats from the falls or davit-blocks with unerring precision, so as to effectually prevent one end being detached before the other, and thereby the risk of loss of life is greatly lessened or prevented.

My invention consists in a hook-ended shaft, supported by slings that are connected together by a semicircular bar, so that the hook-ended shaft can be partially revolved to slip the supporting-rings of the boat-chains off the hooks simultaneously, and thereby detach the boat at both ends simultaneously.

In the drawing—

a a are slings that are supported by the falls or davit-blocks in any usual manner, *b b* representing said blocks, and *c* the upper ends of the davits.

The slings *a a* are firmly connected together by the

semicircular bar *d*, within and against which lies the shaft *e*, that passes through the slings *a*, and terminates with the turned-up or hooked ends *e'*.

Upon these ends *e'* the rings *f* of the boat-chains *g* are hooked, when the hooks *e'* are in the position shown in fig. 1.

Near the middle of the bar *d* are ring-flanges *h*, attached to *d*, and surrounding the shaft *e*, and *k* is a lever firmly attached to the shaft *e*, and *i* is a pin, to be inserted through holes in the flanges *h*, to hold the said hooks *e'* entirely turned up, so as to come in contact at their ends, or nearly so, with the guard-arms *l*, or hold them partially turned up, so that the rings *f* can be hooked upon said hooked ends *e'*.

It will now be understood, that by turning the shaft *e* by the lever *k*, the hooks *e'* will be turned down, so that the rings *f* will be simultaneously and positively slipped off said hooks, and the boat detached at both ends at once.

What I claim, and desire to secure by Letters Patent, is—

The slings *a a*, connected together, so as to be hung from the blocks or fall, in combination with the shaft *e*, hooked ends *e'*, and lever *k*, substantially as and for the purposes set forth.

In witness whereof, I have hereunto set my signature, this 22d day of March, A. D. 1869.

WM. S. RYERSON.
